A. W. LUNDSTROM

ELECTRIC SWITCH BOX

Filed Dec. 22, 1920

Inventor:
Axel W. Lundstrom,
Robert G. Davis
His Attorney.

AXEL W. LUNDSTROM, OF NEW YORK, N. Y., ASSIGNOR TO GENERAL ELECTRIC COMPANY, A CORPORATION OF NEW YORK.

ELECTRIC SWITCH BOX.

Application filed December 22, 1920. Serial No. 432,463.

To all whom it may concern:

Be it known that I, AXEL W. LUNDSTROM, a citizen of the United States, residing at New York, in the county of New York, State of New York, have invented certain new and useful Improvements in Electric Switch Boxes, of which the following is a specification.

The present invention relates to electric switch boxes of the type used to enclose a switch to prevent an operator from coming in contact with the live parts of the switch; an operating handle for the switch projecting out through a wall of the box.

With such structures it is desirable to provide an arrangement whereby the cover of the box can be opened only after the switch has been thrown to off position and whereby the switch cannot be thrown to on position while the cover is open, and the object of my invention is to provide an improved structure and arrangement in an apparatus of this character.

For a consideration of what I believe to be novel and my invention, attention is directed to the accompanying description and the claims appended thereto.

In the drawing, Fig. 1 is a face view of a switch box embodying my invention; Fig. 2 is a section taken on line 2-2, Fig. 1, and Fig. 3 is a view similar to Fig. 1 showing the parts in different positions.

Referring to the drawing, 5 indicates a switch box in which is a base 6 of insulating material. Mounted on base 6 is a switch 7 and fuse holders 8. The switch and fuse holders shown are only by way of example and may be taken as typical of any known or suitable arrangement. The box is divided into a switch compartment and a fuse compartment by a transverse wall or shield 9. The cover of the box comprises a fixed section 10 over the switch compartment and a hinged section 11 over the fuse compartment, section 11 being hinged on section 10 by hinges 12. The operating handle for the switch is indicated at 13 and it projects out through a slot 14 in the fixed cover section 10. Slot 14 is sufficiently long to permit handle 13 to move back and forth in operating the switch. When cover section 11 is opened the fuses are then accessible for renewal or inspection. Shield 9, however, prevents the attendant from access to or accidentally

coming into contact with switch 7. Fixed cover section 10 is fastened to the box by suitably arranged screws as indicated at 15 and may be termed the screwed down portion of the cover. At its end it is provided with a flange 16 having an opening 17 through which projects somewhat loosely a pin or screw 18, the head of which is on the inside of the box.

Fixed on cover section 10 are two spaced plates 19, each provided with a vertically extending flange 20 which flanges are parallel to each other and form a guide or way for a locking member 21. Locking member 21 is formed of a flat strip of metal and has wings 22 at one end which slide along the surfaces of flanges 20. In such wings are holes 23. Locking member 21 is of the same thickness as plates 19, and extending from one plate to the other over the top of member 21 is a guide strip 24 the ends of which are fixed to plates 19. Wings 22 cooperate with flanges 20 to prevent locking member 21 from twisting and strip 24 holds it against the surface of cover section 10. On locking member 21 is printed or stamped the words "Off" and "On" and strip 24 serves to cover the one or the other of these words which indicate whether the switch is open or closed. In locking member 21 is a hole 25 through which switch operating handle 13 projects and as will be clear from the drawing when handle 13 is operated, member 21 will be slid back and forth along the top of cover section 10. Fixed to cover section 11 adjacent its hinged end is a curved nose 26 the end of which projects over fixed cover section 10. When cover section 11 is closed, the end of nose 26 stands spaced from the surface of cover section 11 sufficiently to permit locking member 21 to move under it as shown in Figs. 1 and 2. In fixed cover section 10 is a hole 27 which lies directly under the end of nose 26 and through which nose 26 passes as shown in Fig. 3, when cover section 11 is opened, when the switch is closed the end of member 21 covers hole 27.

At the end of box 5 is fixed a flat post 28 having a hole 29 in its ends. When cover section 11 is closed post 28 passes through a hole 30 in it, and by fastening a padlock or other locking means in hole 29 the cover can be locked shut. The end of cover section 11 is provided with a flange

When the cover section 11 is shut, switch arm 13 can be moved back and forth to open and close the switch, locking member 21 moving with it. When the switch is closed, the end of locking member 21 lies under nose 26 thus preventing the opening of cover section 11, and before cover section 11 can be opened the switch must be moved to open position so as to move the locking member from under the nose. In this connection it will be noted that the end of member 21 lies sufficiently far under nose 26 that the switch handle must have been moved far enough to effect the opening of the switch before it moves from under nose 26 and uncovers hole 27. By this arrangement, therefore, it is not possible to open cover section 11 unless the switch is open. When the switch is open wings 22 extend beyond flanges 20 sufficiently far to uncover openings 23 and by placing a padlock or other locking means in openings 23 the switch can be locked open.

Also by the arrangement shown it is not possible to remove the fixed or screwed down cover section without first throwing the switch to "off" position and opening cover section 11. This is because screw 18 projecting through opening 17 makes it necessary that the cover be slid along the face of the box to move flange 16 beyond the end of screw 18 before the cover can be lifted off and, in order to slide the cover, hinged section 11 must be opened to move its flange 31 free of the end of the box and of post 28. This is illustrated in Fig. 3 where the cover section 11 is shown as having been opened and the cover then slid along to bring flange 16 beyond screw 18. The grip of handle 13 is threaded into the shank so that it may be unscrewed as illustrated in Fig. 3 to permit complete removal of the cover section.

It will be seen that my improved arrangement is simple in structure, positive in operation, and has no parts likely to become deranged. It gives the maximum degree of safety. At the same time it can be manufactured at a low cost.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. In a switch box, the combination of a hinged cover section, a projection on it

adjacent a wall with which the box is opened, a switch in the box, and a locking member which slides on a wall of the box and serves to cover said opening and prevent said projection from entering therein when the switch is closed, and said member being moved to uncover the opening when the switch is opened whereby said projection may pass through the opening and the hinged cover section may be opened.

2. In combination, a switch box having a hinged cover section, a switch in the box having a handle which projects through a wall of the box, a projection on the hinged cover section, and a locking member which slides on a wall of the box and is connected to the switch handle to move therewith, said locking member being moved by the switch handle to a position wherein it holds the projection from movement when the switch is closed and being moved by the switch handle to a position to release the projection when the switch is opened.

3. In combination, a switch box having a hinged cover section, a switch in the box having a handle which projects through a wall of the box, a projection on the hinged section, a locking slide having an opening through which the handle projects whereby said slide moves with the handle, said slide lying in the way of said projection when the switch is closed and being moved out of its way when the switch is opened.

4. In a switch box, the combination of a cover comprising a fixed section and a hinged section, a switch in the box having a handle which projects through the fixed section, a locking member carried by the hinged section, said fixed section having an opening through which it must pass when the hinged section is opened, and a locking member which slides on a wall of the box and is movable with the switch handle, said locking member covering said opening and holding said projection immovable when the switch is closed.

5. In a switch box, the combination of a cover comprising a fixed section and a hinged section, one of said sections having an opening, a locking member on the other section which must pass through said opening when the hinged section is opened, a handle for operating the switch, and a locking member which slides on a wall of the box and is movable with the handle, said locking member covering said opening and holding said first-named locking member immovable when the switch is closed.

6. In a switch box, the combination of a cover comprising a fixed section and a hinged section, said fixed section having a slot and an opening, a switch in the box having a handle which projects through said slot, a locking member carried by the

- 5 said opening when the ring opened, and a locking member which slides on the fixed cover section, said locking member covering said opening and holding the first-named locking member immovable when the switch is closed and being moved by the handle to uncover the opening and release said first-named locking member
- 10 when the switch is opened.
7. In a switch box, the combination of a cover comprising a fixed section and a hinged section, a switch in the box having a handle which projects through the fixed section, a locking member carried by the hinged section, a locking member which slides on the fixed section and lies under the first named locking member, said second named locking member being connected to the switch handle and moved by it under the first-named locking member to hold said member immovable when the switch is closed and from under said first named locking member to permit said member to move when the switch is opened.
- 15 8. In a switch box, the combination of a cover comprising a fixed section and a hinged section, said fixed section having a slot, a switch in the box having a handle which projects through said slot, a locking projection on the hinged cover section, and a locking member which slides on the fixed cover section and is connected to the switch handle to move therewith, said locking member lying in the way of said locking projection and holding said projection immovable when the switch is closed and being moved out of the way of said projection when the switch is opened.
- 20 9. In a switch box, the combination of a cover comprising a fixed section and a hinged section, said fixed section having a slot, a switch in the box having a handle which projects through said slot, a locking projection on the hinged cover section, a locking member which slides on the fixed cover section and is connected to the switch handle to move therewith, said locking member lying in the way of said locking projection when the switch is closed and being moved out of its way when the switch is opened, guide means, and guide wings carried by the locking member and cooperating with said guide means, said guide wings having an opening adapted to receive a lock for locking the switch open.
- 25 10. In a switch box, the combination of a handle which projects through the fixed section, a locking member carried by the hinged section, a locking member which slides on the fixed section, said second named locking member being connected to the switch handle and moved by it into and out of the way of the second named locking member when the switch is closed and opened, and means preventing the removal of the fixed cover section without first opening the hinged cover section.
- 30 11. In a switch box, the combination of a screwed down cover section, a hinged cover section, said sections being each provided with flanges at their ends which lap over adjacent switch box walls when the cover sections are closed, a stud carried by a switch box wall and projecting through an opening in the flange of the screwed down cover section whereby in order to remove both cover sections the hinged cover section must be opened and the sections slid along the box, and locking means for the hinged section which prevents its being opened except when the switch is open.
- 35 12. In combination, a switch box having a removable cover, said cover having a hinged section normally closed, a fixed section normally secured to the box and flanges at its edges which lie about and enclose the adjacent edges of the box, a switch in the box having a handle which projects through a slot in the fixed section of the cover, a projection on the hinged cover section which must move through an opening in the fixed cover section when said hinged section is moved from the closed position, a sliding strip guided on and supported by the fixed cover section and connected with the switch handle whereby it is moved in response to movement of the switch handle, said sliding strip being moved to a position between said projection and the opening when the switch is moved from the open position, and a stud carried by a wall of the switch box and projecting through an opening in an adjacent flange of the cover, whereby in order to remove the cover the hinged cover section must be opened and the cover slid along the box in the direction of the stud.
- 40 45 50 55 60 65 70 75 80 85 90 95 100 105 110

In witness whereof, I have hereunto set my hand this 20th day of December, 1920.

AXEL W. LUNDSTROM.
